UNITED STATES PATENT OFFICE.

JACOB B. ROSE, OF CLEVELAND, OHIO, ASSIGNOR TO THE OSBORN-CREW MANUFACTURING COMPANY, OF CLEVELAND, OHIO, A CORPORATION OF OHIO.

SUPPORTING DEVICE.

Application filed October 13, 1921. Serial No. 507,529.

To all whom it may concern:

Be it known that I, JACOB B. ROSE, a citizen of the United States, residing at Cleveland, in the county of Cuyahoga and State 5 of Ohio, have invented a certain new and useful Improvement in Supporting Devices, of which the following is a full, clear, and exact description.

The present invention relates to a support 10 which is adapted to be fastened in an elevated vertical position as to a wall or molding.

The support is particularly intended as a garment or apparel support, although not 15 limited in this respect, and furthermore, the support finds particular usefulness where it is desired to not have garment supporting hooks extending out from the wall except when in use, as for instance in narrow passageways where protruding hooks are liable 20 to be hit against by passersby.

The present invention provides a supporting member which is resiliently maintained in a vertical position and inside of a depression 25 in a casing which is associated with it, the hook being so mounted as to be capable of being moved to a substantially horizontal position when in use and as soon as the weight is released from the hook, the same 30 immediately returns to its vertical position.

The particular construction which forms the present invention provides that the resilient feature by which the support is to be turned to vertical position is obtained by 35 making the supporting member of resilient wire material, which is distorted when the support is in horizontal position, and as soon as the weight is relieved, the metal of the supporting member under its own inherent 40 resiliency returns to its initial position.

Reference should be had to the accompanying drawings forming a part of this specification in which Fig. 1 is a front elevation of a device embodying the present 45 invention; Fig. 2 is a front elevation with the supporting member in distended position; Fig. 3 is a sectional elevation.

Referring to the drawings, 1 indicates a suitable base which may conveniently be 50 formed as a stamping and has a face portion 2 which contains a depression 3 within which lies the supporting member 4. The configuration of the depression 3 is immaterial but is preferably such as to substantially follow the contour of the support-

ing member 4. The bottom of the depression 3 which is substantially as deep as the height of the slanting sides bordering on the face 2 are holes 5 which are adapted to receive screws or nails for the purpose of 55 fastening the device to a wall or similar object when in use.

The supporting member 4 normally lies practically entirely within the depression 3 so that there is nothing protruding from the base member 1 except at the extreme end of the hook which does extend beyond the casing a very slight amount so as to enable a finger of a person desiring the use of the hook to be inserted beneath the supporting 70 member and pull it outwardly.

The supporting member 4 is formed as a looped member its free ends extending at right angles to the long axis of the supporting member, which ends are indicated in dotted lines in Fig. 1 at 4^a. Additionally, the supporting member 4 near to the outwardly extending portions 4^a is provided with an oppositely disposed outwardly extending projection 4^b, which may be conveniently 75 formed, when the supporting member is formed of wire, by bending the wire upon itself as clearly indicated in Fig. 1.

In its preferred form, the supporting member 4 is made out of wire which is inherently resilient, that is to say, of wire which when deformed from its natural position, will tend to return to its former position.

The outwardly extending members 4^a pass 90 through oppositely disposed holes in side walls of the lower portion of the depression 3, and additionally it is to be noted that the lower side walls of the depression 3 are slanting inwardly or toward each other as 95 indicated at 3^a and it should further be noted that the extensions 4^b which are formed on the supporting member 4 are in such position that when the support member 4 is pulled forwardly these extensions 4^b will tend to ride 100 along the surfaces of the walls 3^a thereby acting as cam members which serve to move the members 4^b toward each other, and this will continue until the support is pulled downwardly as far as it will go. If after pulling outwardly and downwardly the member 4, it be released, it will immediately return to its initial position due to the inherent resiliency in the member 4.

Therefore after a garment has been re- 110

moved from the supporting member, no further attention may be paid to it as it automatically returns to its initial position.

By providing the resilient feature of the support as an inherent property of the supporting member itself makes it possible to greatly reduce the cost of production of such devices, at the same time making them more efficient, due to the elimination of any 10 small springs in connection with the device.

While the device shown in the drawings is the preferred form, it will be understood that in speaking of the supporting member 4 as resilient, it is intended to include a condition not only where the supporting member is inherently resilient, but where it is not 15 resilient and a resilient member or members are employed to make it resilient.

Having described my invention, I claim—

20 1. In a device of the character described, a base member, a supporting member pivotally mounted at one of its ends on said base, said base being provided with surfaces adapted to be engaged by the supporting member as 25 it is moved on its pivot to thereby deform said supporting member from its natural position, whereby the supporting member returns to its initial position when released.

20 2. In a device of the character described, a base member, a supporting member pivotally mounted at one of its ends on said base, said base being provided with slanting surfaces adapted to be engaged by portions 35 of the supporting member adjacent the pivotal mounting thereof, and thereby to deform said supporting member from its natural position so that the supporting member returns to its initial position when released.

30 3. In a device of the character described, a base member provided with a depression which has slanting side portions at one end thereof, a resilient supporting member which is pivotally mounted at one of its ends in the said depression of the base member, said 45 supporting member having parts adapted to engage with the slanting surface before mentioned to thereby deform said supporting member as it is moved on its pivot, whereby the supporting member returns to its initial position when released.

40 4. In a device of the character described, a base member, a looped supporting member having its free ends extending away from

each other, said base member being provided with oppositely disposed openings through 55 which the projections on the end of the supporting member extend, said base member being provided with surfaces adjacent the place where the supporting member is pivoted, which surfaces are engaged by the supporting member as it is moved about its pivot to thereby deform said supporting member, whereby the supporting member returns to its initial position when released.

5. In a device of the character described, a base member, a loop-shape supporting member supporting a loop-shaped resilient supporting member which at its free end is formed with outwardly and oppositely projecting extensions, said base provided with a depression in which the said supporting member normally lies, said base member being provided with oppositely disposed openings in walls of the depression which are adapted to receive the outwardly extending 70 portions of the supporting member, the walls of said depression adjacent the pivotal point of the supporting member being inclined and adapted to engage with the supporting member when the same is moved about its pivot thereby to deform the supporting member whereby the supporting member returns to its initial position when released.

6. In a device of the character described, a base member, said base member having a depression therein, the outside walls of said depression at one end being slanting and having two oppositely disposed holes therein, a resilient supporting member formed of a wire formed as a loop, the free ends of the wire being bent outwardly and in opposite directions, said wire having sidewardly extending projecting portions above the free ends, the said supporting member normally lying in the depression in the base member 95 with the outwardly extending free ends passing through the holes aforesaid and with the outwardly extending projections on the supporting member engaging the slanting surfaces of the depression when the supporting member is moved thereby to place the resilient member under tension.

In testimony whereof I hereunto affix my signature.

JACOB B. ROSE.
